(57) **CLAIM**

(51) LOC (7) Cl. **12-16**

The ornamental design for an illuminated display and turn
signal apparatus, as shown and described.

(52) U.S. Cl. **D12/162; D20/10**

DESCRIPTION

(58) Field of Search **D12/162, 400,**

FIG. 1 is a perspective view of the illuminated display and
turn signal apparatus showing my new design with a lens
exploded therefrom;

**D12/203; D20/10, 42; D26/28, 31, 34,
36; 40/204-205, 541-542, 209, 544, 564,
584, 590-591, 611.1, 618, 575, 211; 280/495,
504, 506-507, 511, 727; 293/122; 340/468-479;
362/459-460, 484-487, 495-499, 505-506,
269, 275, 427-428, 418-419; 138/89-89.4;
224/524, 522, 527**

FIG. 2 is a top plan view of the illuminated display and turn
signal apparatus of FIG. 1;

FIG. 3 is a rear plan view of the illuminated display and turn
signal apparatus of FIG. 1;

FIG. 4 is a bottom plan view of the illuminated display and turn
signal apparatus of FIG. 1;

FIG. 5 is a front plan view of the illuminated display and turn
signal apparatus of FIG. 1; and,

FIG. 6 is a plan side view of the illuminated display and turn
signal apparatus of FIG. 1.

The broken line showing of environment is for illustrative
purposes only and forms no part of the claim design.

FIGS. 2-5 are shown on an enlarged scale as compared with
FIG. 1.
